UNITED STATES PATENT OFFICE

155,959

DESIGN FOR A DISPENSING UNIT FOR FILLING STATIONS

Wilbur H. Adams, Erie, Pa., assignor to Erie Meter
Systems, Inc., Erie, Pa., a corporation of Penn-
sylvania

Application November 12, 1947, Serial No. 142,485

Term of patent 14 years

(Cl. D52—2)

To all whom it may concern:

Be it known that I, Wilbur H. Adams, a citizen of the United States, residing at Erie, in the county of Erie and State of Pennsylvania, have invented a new, original, and ornamental Design for a Dispensing Unit for Filling Stations, of which the following is a specification, reference being had to the accompanying drawing, forming a part thereof.

Fig. 1 is a front view and Fig. 2 is a side view of a dispensing unit for filling stations, showing my new design. The rear of the dispensing unit is substantially the same in appearance as the front, and the side not shown is substantially the same as the side shown.

The dominant portion of the design resides in the solid line disclosure.

I claim:

The ornamental design for a dispensing unit for filling stations, substantially as shown and described.

WILBUR H. ADAMS.
